**ARCHITECTURAL ENGINEERING PENCIL
SHARPENER**

Talat Tufan, Brooklyn, N.Y., assignor to
Zottos L. Papanidis, New York, N.Y.
Filed Apr. 23, 1964, Ser. No. 361,959
6 Claims. (Cl. 120—89)

This invention relates generally to pencil sharpeners and more particularly to a combined pencil sharpener or pointer and refuse receptacle, especially designed to be used by draftsmen, architects, engineers and artists.

Ordinary pencil sharpeners or pointers when used freely liberate graphite dust which is variously scattered on the table, desk, floor, wastebasket, etc., causing soiling and smudging of everything it contacts, including the hands of the user.

A primary object of the present invention is to provide a pencil sharpener or pointer of the enclosed character which is so shaped and so light in weight to permit it to be placed on top of a supporting surface convenient to an individual user.

Another object of the invention is to provide a pencil sharpener or pointer of the character described which is capable of serving as a receptacle for pencil refuse and is provided with a trap chamber so as to retain the refuse in case it is accidentally turned upside down or upset.

A further object is to provide a pencil sharpener or pointer of this character that can be readily emptied and cleaned.

It is also an object of the invention to provide a pencil sharpener or pointer of this character that is simple and rugged in construction and is economical to manufacture.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

FIG. 1 is a top perspective view of a pencil sharpener and refuse receptacle embodying one form of the invention, the cover being shown removed and a pencil being shown preparatory to being sharpened.

FIG. 2 is a cross-sectional view taken on the line 2—2 of FIG. 1, with the cover in closed position.

FIG. 3 is an exploded perspective view thereof, parts of the container being shown broken away.

FIG. 4 is a sectional view through the longitudinal center thereof, the cover being omitted.

FIG. 5 is a view similar to FIG. 1 of a pencil sharpener and refuse receptacle embodying a modified form of the invention.

FIG. 6 is a sectional view taken on the line 6—6 of FIG. 5.

FIG. 7 is a view similar to FIG. 2 of the device of FIG. 5, parts being shown broken away.

FIG. 8 is a top perspective view of a pencil sharpener or pointer and refuse receptacle embodying another modified form of the invention, parts being shown detached.

FIG. 9 is a cross-sectional view taken on the line 9—9 of FIG. 8 showing a pencil preparatory to being sharpened.

Referring now in detail to the various views of the drawings, in FIG. 1 a combined pencil sharpener or pointer and refuse receptacle is shown and designated generally at 10. The device 10 comprises a housing or casing 12 formed of plastic or other suitable material. The housing has a bottom wall 14, side walls 16, 16 and end walls 18, 18 the side walls slanting inwardly. The end walls are formed with opposed notches 20 at the top

2

center thereof. The side and end walls define an open top which is adapted to be closed by a closure plate 22 having a peripheral flange 24. The housing is rectangular in plan and may be of any desired dimensions, but preferably is approximately 3½" long, 1¾" high, 2¼" wide at the bottom and 1¾" wide at the top.

In accordance with the invention the sharpening and pointing mechanism is mounted at the top of the housing, interiorly thereof. This mechanism includes a plurality of elongated rectangular-shaped metal plates 26 disposed alongside of each other in slanting relationship and held together against displacement by triangular-shaped bearing plate members 28, 28 interlocked to the ends of the plates 26 by means of radial grooves 30 on the inner surfaces of the bearing members coacting with reduced end edges 32 on the plates. Trunnions 34 extend outwardly of cylindrical bases 36 secured to the centers of the bearing members on the outer surfaces thereof by means of adhesive 38 or the like. Knobs or finger pieces 40 are removably mounted on the free ends of the trunnions.

On one side of each plate 26, the surface thereof is covered with a strip of sandpaper 42 fastened thereon by suitable adhesive, and on the opposite side the surface is covered with a soft flexible strip 44 of felt or the like secured thereto by adhesive. The arrangement of the plates is such that a surface of sandpaper is disposed adjacent to a surface of felt as seen in FIG. 2 so that there is always a sharpening surface and a cleaning surface exposed.

30 In use, the exposed portion of the lead L of a pencil P is moved back and forth over the sandpaper 42 to sharpen and point the pencil. As the lead is sharpened the particles of lead gravitate into the trough formed by adjacent plates 26. Subsequently, the pencil is moved 35 back and forth over the felt strip 44 so that the loosened particles will be brushed or wiped from the lead. The sharpening and pointing mechanism is then rotated on the trunnions 34 by means of one of the knobs 40 and the particles of lead and shavings in the trough are 40 dumped into the interior of the housing or casing 12 and collected on the bottom wall 14. The plates 26 are mounted within the housing or casing 12 and extend from end to end thereof and as such trap and retain all refuse deposited in the casing or housing if the casing or housing 45 is upset.

The sharpening and pointing mechanism is removable as a unit by lifting it upwardly carrying the trunnions 34 out of the bearing notches 20. When the mechanism is removed, the casing and housing may be readily cleaned 50 and emptied of the refuse collected.

The modified form of combined pencil sharpener or pointer and refuse receptacle 10' shown in FIGS. 5 to 7, inclusive, differs from the device 10 in that the triangular-shaped bearing members 28' are held together by 55 means of an elongated round shaft 50 extending through central holes 52 therein and protruding outwardly thereof. The protruding ends 54 of the shaft are journaled in U-shaped bearing members 56 formed on the inner surface of the end walls 18' at the top center thereof. 60 The pencil sharpening and pointing mechanism is rotated by merely pressing downwardly on the surface of the plates 26' by the finger of the user. No turning knobs such as knobs 40 are needed.

In all other respects, the combined pencil sharpener or pointer and refuse receptacle 10' is similar to device 10 and similar reference numerals are used to indicate similar parts throughout.

Referring now to the modified form of pencil sharpener or pointer and refuse receptacle 10" shown in FIGS. 8 and 9, this modification differs from device 10' in that the bottom wall 14" is formed separately with

an upstanding flange 60 therearound. The side and end walls 16" and 18", respectively, are formed integrally with each other and are supported on the bottom wall outwardly of the flange 60, the flange serving as a guide in positioning the same. In this form, the side walls 16" terminate short of the top of the end walls 18".

A pair of downwardly slanting top walls 62, 62 are formed integrally with the top edge of the side walls 16". The top walls extend downwardly and inwardly into the interior of the casing to a point approximately the midheight of the casing, the free ends of said slanting top walls being closely spaced from each other, providing a clearance 64 for the particles of lead and shavings to fall by gravity into the interior of the casing onto the bottom wall 14". The upper or outer surfaces of the slanting walls are recessed for their length as indicated at 66 and covering the recesses are strips of sandpaper or files 68 removably secured in place by adhesive 70.

In this form, the flanged bottom wall 14 serves as a tray for collecting the particles of lead and shavings and when it is desired to clean and empty the tray, the side, end and top walls are lifted as a unit off of the bottom wall.

While I have illustrated and described the preferred embodiments of my invention, it is to be understood that I do not limit myself to the precise constructions herein disclosed and that various changes and modifications may be made within the scope of the invention as defined in the appended claims.

Having thus described my invention, what I claim as new, and desire to secure by United States Letters Patent is:

1. In a combined pencil sharpener and refuse receptacle, the combination of a rectangular housing having bottom, side and end walls, said side and end walls defining an open top, said end walls having notches in the top edges thereof, an assembly of slanting rectangular plates rotatably mounted at the top of the housing interiorly thereof, said mounting including triangular plates on the ends of the rectangular plates for holding said rectangular plates together, and trunnions extending from the triangular plates, said trunnions being journaled in the notches in the top edges of the end walls, said slanting plates having abrasive surfaces on one side, and means for rotating said assembly to discharge refuse to the bottom of the housing.

2. In a combined pencil sharpener and refuse receptacle, the combination of a rectangular housing having bottom, side and end walls, said side and end walls defining an open top, said end walls having notches in the top edges thereof, an assembly of slanting rectangular plates rotatably mounted at the top of the housing interiorly thereof, said mounting including triangular plates on the ends of the rectangular plates for holding said rectangular plates together, and trunnions extending from the triangular plates, said trunnions being journaled in the notches in the top edges of the end walls, said slanting plates having abrasive surfaces on one side, and means for rotating said assembly to discharge refuse to the bottom of the housing, said assembly being removable as a unit from the housing.

3. In a combined pencil sharpener and refuse receptacle, the combination of a rectangular housing having bottom, side and end walls, said side and end walls defining an open top, said end walls having notches in the top edges thereof, an assembly of slanting rectangular plates rotatably mounted at the top of the housing interiorly thereof, said mounting including triangular plates on the ends of the rectangular plates for holding said rectangular plates together, and trunnions extending from the triangular plates, said trunnions being journaled in the notches in the top edges of the end walls, said slanting plates having abrasive surfaces on one side, and means for rotating said assembly to discharge refuse to the bottom of the

housing, said assembly being removable as a unit from the housing, said rotating means including at least one knob on one of the trunnions outwardly of an end wall of the housing.

5. In a combined pencil sharpener and refuse receptacle, the combination of a rectangular housing having bottom, side and end walls, said side and end walls defining an open top, said end walls having notches in the top edges thereof, an assembly of slanting rectangular plates rotatably mounted at the top of the housing interiorly thereof, said mounting including triangular plates on the ends of the rectangular plates for holding said rectangular plates together, and trunnions extending from the triangular plates, said trunnions being journaled in the notches in the top edges of the end walls, said slanting plates having abrasive surfaces on one side, and means for rotating said assembly to discharge refuse to the bottom of the housing, said slanting plates having wiping felt surfaces on the opposite sides thereof.

20 6. In a combined pencil sharpener and refuse receptacle, the combination of a rectangular housing having bottom, side and end walls, said side and end walls defining an open top, said end walls having notches in the top edges thereof, an assembly of slanting rectangular plates rotatably mounted at the top of the housing interiorly thereof, said mounting including triangular plates on the ends of the rectangular plates for holding said rectangular plates together, and trunnions extending from the triangular plates, said trunnions being journaled in the notches 25 in the top edges of the end walls, said slanting plates having abrasive surfaces on one side, and means for rotating said assembly to discharge refuse to the bottom of the housing, said assembly being removable as a unit from the housing, said rotating means including at least one knob on one of the trunnions outwardly of an end wall of the housing, said slanting plates having wiping felt surfaces on the opposite sides thereof.

30 7. In a combined pencil sharpener and refuse receptacle, the combination of a rectangular housing having bottom, side and end walls, said side and end walls defining an open top, an assembly of sharpening and cleaning plates rotatably mounted at the top of the housing interiorly thereof, said mounting including an elongated shaft, triangular plates on the ends of the shaft, the ends of the shaft projecting outwardly of the triangular plates, opposed V-shaped bearing members on the inner surfaces of the end walls centrally thereof at the top, the projecting ends of the shaft journaled in said bearing members, said sharpening and cleaning plates constituted by rectangular-shaped plates secured at the ends to said triangular-shaped plates in side-by-side and slanting relationship, said slanting rectangular-shaped plates having abrasive surfaces on one side and wiping felt surfaces on the opposite sides, said assembly adapted to be rotated by exerting downward pressure on one of the slanting rectangular plates for dumping the refuse into the bottom of the housing, said assembly being removable as a unit from the housing.
